UNITED STATES PATENT OFFICE

GEORGE M. GIBSON, OF PELLA, IOWA, ASSIGNOR TO WOODROW WASHING MACHINE COMPANY, OF PELLA, IOWA, A CORPORATION OF IOWA

GEARING MECHANISM FOR WASHING MACHINES

Application filed August 6, 1928. Serial No. 297,824.

The object of my invention is to provide a gearing mechanism for washing machines of simple, durable and inexpensive construction, which is easily manufactured and assembled, and when assembled is of compact form.

A further object is to provide in a washing machine mechanism, including an agitator shaft adapted to be oscillated, improved mechanism for oscillating the said agitator shaft and for reducing excessive noises caused by the back lash of the gear mechanism.

A further object is to provide in a washing machine mechanism, employing a reciprocating mechanism operated from a continuous rotary mechanism, improved means for connecting the rotating mechanism with the oscillating mechanism.

A further object is to provide a washing machine mechanism housed in a casing having upper and lower sections, which may be separated and so arranged that the gearing may be assembled in the separated sections and completely assembled by placing the sections together, and when so placed will form a grease tight compartment for the mechanism contained therein.

My invention consists in the construction, arrangement and combination of the various parts of the device, whereby the objects contemplated are attained, as hereinafter more fully set forth, pointed out in my claims, and illustrated in the accompanying drawings, in which:

35 Figure 1 is a vertical sectional view of my improved mechanism showing the manner in which it is applied to a washing machine.

Figure 2 is a detail sectional view taken on the line 2-2 of Figure 1.

40 Figure 3 is a detail sectional view taken on the line 3-3 of Figure 1.

In the drawings I have illustrated a washing machine having a tub 10 provided with a bottom 11 and supporting legs 12. A motor platform 13 is carried by the lower ends of the legs 12, on which is mounted an electric motor 14 of the ordinary type having a belt pulley 15.

45 The washing machine bottom 11 is provided with a vertically arranged agitator

shaft 16 having one end projecting upwardly into the tub 10 and provided with an agitator 17 adapted to oscillate about the axis of the shaft 16.

50 My improved washing machine gearing is supported in a casing comprising a bottom section 18 and a top section 19, said sections being supported below the bottom of the tub 10 in the manner clearly illustrated in Figure 1. Said casing is supported by brackets 20 secured to the tub 10 by suitable bolts or rivets.

The sections 18 and 19 are provided with flanges 21 and 22 secured together by bolts 23. The bottom section 18 has bearings 24, 25 and 26. The bearing 24 is designed to support the lower end of the agitator shaft 16 which projects through a bearing 27 in the top section. The said agitator shaft 16 has a rock arm 28 fixed to said shaft. The outer end of the rock arm is provided with a vertically arranged opening 29.

55 The bearing 25 is provided with a vertically arranged shaft 30 designed to support a crank gear 31 having an opening 32. The distance between the center of the shaft 25 and the center of the opening 32 is less than the distance between the center of the shaft 16 and the opening 29.

60 Said openings 29 and 32 are designed to receive wrist pins 33 and 34 of a link 35. Said wrist pins are supported in a common plane with the said link and parallel with each other and project in the same direction, so that the link may be easily and quickly 65 placed in position with the pins 33 and 34 in the openings 32 and 29. When the top section of the casing is removed, the link is mounted close to the top and needs no other means for retaining the pins in their respective openings.

65 Rotatively supported in the bearing 26 is a vertical shaft 36, which also extends upwardly through the top of the section 19 and is provided at its lower end with a worm gear 37 fixed thereto. The worm gear 37 is designed to mesh with a worm pinion 38 mounted on a horizontally arranged driving shaft 39, which has its outer end provided with a belt pulley 40 designed to carry a 70

belt 41 driven from the motor pulley 15. The upper face of the worm gear 37 is provided with a series of radially arranged and upwardly projecting lugs 42. The central portion of the gear 37 is provided with a hub 43, the upper end of which is provided with a friction face 44.

Slidably and rotatively mounted on the shaft 36 is a gear 45 in mesh with the gear 31, and having its under side provided with notches 46 for receiving the lugs 42 of the gear 37. The central portion of the gear 45 is provided with a friction surface to engage the friction surface 44 of the gear 37, at the time the lugs 42 are in the notches 46. The lugs 42 are so proportioned that a slight clearance is provided between the top of the lugs and the bottom of the notches 46 to permit the two friction surfaces to be brought into contact. Said surfaces are yieldably supported in frictional relation by means of a spring 47 on the shaft 36, one end of which rests against the top of the casing 19 and the other end against the gear 45.

The upper side of the gear 45 is provided with a hub 48 having an annular groove 49 for receiving a yoke 50 mounted on the lower end of a vertically arranged operating rod 51, said rod being slidably mounted in the top of the casing 19.

The parts are so arranged that as the rod 51 is elevated, the gear 45 will also be elevated, so that the lugs 42 will be drawn out of the notches 46. Thereby providing means whereby the gears 45 and 37 may be thrown out of operative relation with each other, and provides means for throwing the washing machine into and out of operation. The gears 31 and 45 are of such width that when the gear 45 is at its upper limit of movement, the teeth of said gears will still be in mesh.

By this arrangement it will be seen that if the gear 45 is moved to its lower limit of movement, the friction faces between said gears will be supported in frictional contact, and if the motor 14 is operated, the worm 38 will be rotated through the belt 41 and in turn the gear 45 rotated, causing the gear 31 to rotate and the arm 28 to be oscillated through the link 35, which in turn will oscillate the agitator shaft 16.

It will be seen that as the gear 31 is rotated and the pin 33 of the link 35 passes dead center, then reverse movement will be imparted to the link 35, which will cause a clicking between the teeth of the gears 45 and 31, due to the back lash of said gears. This clicking sound is annoying as well as destructive to the gear teeth.

By providing frictional contact between the frictional surfaces of the gears 45 and 37, I have provided means whereby excessive knocking between the teeth will be modified, and at the same time eliminating the clicking noise, and thereby prolonging the life

of the gears as well as eliminating the disagreeable noise.

My gear mechanism is assembled by first mounting the agitator shaft 16 together with its arm 28 in the bearing 24, then mounting the shaft 30 in the bearing 25 and the gear 31 on the shaft 30. The link 35 may then be mounted with the wrist pins 33 and 34 in their respective openings. The shaft 39 and the worm 38 are also mounted in the casing 18, while the shafts 51 and 36 are mounted in the casing 19 with the respective gears and mechanism connected thereto, after which the casing 19 may be placed in position on the casing 18 with the lower end of the shaft 36 in the bearing 26, and the gear 45 in mesh with the gear 31, and the gear 37 in mesh with the gear 38.

Thus it will be seen that I have provided a washing machine gear of comparatively cheap construction, due to its simplicity and which may be easily and quickly assembled, and when assembled is very positive in its operation, and in which excessive wear and noise, due to reversing of the oscillating mechanism, are largely eliminated.

I claim as my invention:

1. A gearing mechanism for washing machines including a shaft having a continuous driving member, one face of said member being provided with laterally projecting radial lugs and a friction surface, a driven member rotatively mounted and adapted to move toward and from the first said member and provided with notches for receiving lugs of the first said member, and a friction surface for coacting with the first friction surface, an agitator shaft, means operated by the driven member for imparting a rotary oscillatory movement to said agitator shaft, and means for yieldably supporting said friction faces in operative relation.

2. In a gearing mechanism for washing machines, a supporting casing, a shaft, a driving member mounted to rotate continuously with said shaft including clutch elements and a friction surface, a driven member rotatively and slidably mounted on said shaft having clutch elements and a friction surface to coact respectively with the clutch elements and friction surface of the driving member, means for yieldably supporting said friction surfaces in operative relation when the clutch elements are in operative relation, means for throwing said clutch elements and said friction elements out of operative relation, an agitator shaft, and means actuated by said driven member for imparting a rotary oscillatory movement to said agitator shaft.

3. A gearing mechanism for washing machines comprising a casing divided into upper and lower sections, a horizontal driving shaft rotatively mounted in the lower section, a worm pinion on said shaft, a vertical shaft rotatively mounted in said upper and lower

sections, a worm gear on said vertical shaft in mesh with said worm pinion, the upper surface of said worm gear having upwardly projecting lugs, a spur gear rotatively and slidably mounted on said vertical shaft having its under surface provided with notches for receiving the lugs of the first said gear, a second vertical shaft, a crank gear on said second shaft in mesh with said spur gear, a vertical agitator shaft having a rock arm, provided with an opening in its free end, said crank gear also being provided with an opening, a link having a laterally projecting wrist pin at each end, said wrist pins being mounted in said openings for operatively connecting said crank gear and said arm, means for sliding the spur gear toward and from the worm gear to cause the lugs to engage and disengage said notches, and means for yieldingly retaining the driven gear at its inner limit of movement.

4. A gear mechanism for washing machines comprising a casing divided into upper and lower sections, a horizontally arranged shaft rotatively mounted in the lower section, a worm pinion on said shaft, a vertical shaft rotatively mounted in said upper and lower sections, a worm gear on said shaft in mesh with said worm pinion, the upper surface of said worm gear having upwardly projecting lugs and a friction surface, a spur gear rotatively and slidably mounted on said vertical shaft having its under surface provided with notches for receiving the lugs of the first said gear, and a friction surface to coact with the first said friction surface, yieldable means for retaining said friction surfaces in operative relation, means for separating said friction surfaces and said lugs and notches, a second vertical shaft, a crank gear mounted on said second shaft in mesh with the said driven gear, an agitator shaft having a rock arm, and a link for operatively connecting the free end of said arm with said crank gear.

45 5. In a gearing device for washing machines, a supporting casing, a driving member mounted to rotate continuously including a clutch element and a friction surface, a driven member rotatively mounted concentrically with and adjacent to the driving element having a clutch element and a friction surface to coact with the clutch element and friction surface of the driving member, means for yieldably supporting said friction surfaces in operative relation when the clutch elements are in operative relation, means for moving the clutch element and friction surface of one member out of operative relation with the clutch element and friction surface of the other member, an agitator shaft, and means actuated by said driven member for imparting rotary oscillatory movement to said agitator shaft.

Des Moines, Iowa, May 17, 1928.
